(57) **CLAIM**

The ornamental design for a cosmetic product container, as shown and described.

DESCRIPTION

FIG. 1 is a front elevational view of a cosmetic product container showing my design; FIG. 2 is a left side elevational view thereof; FIG. 3 is a right side elevational view thereof; FIG. 4 is a rear elevational view thereof; FIG. 5 is a top plan view thereof; and, FIG. 6 is a bottom plan view thereof.

(Continued)

The broken line shown in the figure drawings are included for the purpose of illustration and form no part of the claimed design.

The stippling in FIGS. 1-6 shows contrast in appearance.

1 Claim, 3 Drawing Sheets
